METHOD OF MAKING SAFETYPINS

Frank Magidson, Pittsburgh, Pa.

Application March 20, 1935, Serial No. 11,957

6 Claims. (Cl. 163—7)

This invention relates to safety pins of the unitary type, i. e., pins made from a single length of wire stock, and to methods of making the same.

5 An object of this invention is the provision of a safety pin that shall be of unitary construction, strong, efficient and durable.

Another object of the invention is the provision of a unitary pin that may be manufactured 10 at lower cost than prior art pins having a separately formed head and guard, and which may be more easily manufactured than such prior art pins, and which admit of continuous and uninterrupted production on automatic machines.

15 A further object of the invention is to provide a method of gathering metal at the end of a wire, which will insure that a sufficient amount of metal may be available at the proper place to permit the formation of a head on the safety pin that will have adequate size and clearances 20 to retain the pin point in a safe position when closed or locked.

Other objects of the invention will in part be apparent and will in part be obvious from the 25 following description taken in conjunction with the accompanying drawing in which:—

Figure 1 is a more or less diagrammatic view of apparatus employed in feeding wire stock to a gathering die which forms a gather or ball of metal from which the cup or head of the safety pins are formed in accordance with this invention;

30 Figs. 2 to 6, inclusive, show a series of steps employed in the manufacture of safety pins in accordance with this invention, Fig. 6 depicting both the last step and the finished pin;

Figs. 7 to 11, inclusive, show another series of steps which may be employed in the manufacture of pins in accordance with this invention, the 40 steps depicted by Figs. 10 and 11 being the reverse of the steps depicted by Figs. 5 and 6, Fig. 11 depicting both the last step and the finished pin;

Fig. 12 is a bottom view showing the shape and form of the cup of the pins as formed by the 45 steps depicted in Figs. 3 and 8;

Fig. 13 is an end view of this cup as seen looking in the direction of arrows XIII—XIII; and

Fig. 14 is a view showing a modified form of pin which may be made in accordance with this 50 invention.

Throughout the drawing and the specification, like reference characters indicate like parts.

For convenience, the article, that is, the safety pins of this invention, will first be described as 55 it is believed that the description of the methods

of making the same and their advantages may then be more easily understood.

In the drawing, two forms of safety pins are illustrated, one form being shown in Figs. 6 and 11 and the other in Fig. 14. Since the method 5 involved in the making of the pins of Figs. 6 and 11 and 14 differ in certain steps, these pins are designated by reference characters 1, 1' and 2, respectively.

Since pins 1 and 1' are similar in shape and 10 form corresponding parts will be designated by the same reference characters. Pins 1 and 1' are each unitary in construction, being made from a single length of wire, for example, spring steel, and comprise a back bar 3, a bar pin 4 having a pin point 5, a coil spring portion 6 and a head 7. Head 7 comprises a cup 8 of channel shape having spaced relatively deep lips 9, a closely bent return-loop 10 of substantially U-shape and a guard 11 which extends from the 15 back bar 3 into the cup 8 but in spaced relation to the bottom and lips thereof. It is preferred that the guard 11 shall extend at right angles to the back bar and enter cup 8 at about its middle. The guard 11 and loop 10 are so formed that the 20 pin point 5 may enter the cup from either side of the guard when closing the pin and so that the pin point may pass under the guard to facilitate opening thereof.

In forming the pin, the bar pin 4 is made of 30 such length that the extreme point of the pin will project a slight distance past the rear end of the cup as indicated at 12 in Figs. 6 and 11. When the cup is formed, the groove or channel defined by lips 9 extends beyond the lips and 35 into the lower bar of loop 10, as indicated by broken line 13. This extended groove serves to further increase the seating surface for the pin point and to further protect the same.

From the above, it is seen that the safety pin 40 is unitary throughout as all parts thereof are formed from the same piece of stock. It will also be observed that because of the closely bent return loop 10, a strong head is provided which is highly resistant to the forces imposed thereon 45 by the spring of the bar pin which tends to distort and bend the head. To further increase the stiffness and strength of the head, it is preferred to make the return bend loop 10 as short as possible in respect to dimension L.

Pin 2 differs from pins 1 and 1' merely in the shape of the loop which joins the cup to the guard, and for this reason similar parts will be designated by prime reference characters. Cup 8' is joined to guard 11' by means of a loop 15 which 55

is substantially circular and of a diameter materially less than the distance between the back bar 3' and bar pin 4'. By making this loop of small diameter, sufficient stiffness and strength 5 are provided to nullify the normal bending loads imposed thereon when the pin is closed. As stated previously, it is this bending load which tends to distort and open the heads of safety pins.

The method employed in the making of pin 1 10 includes among other things the accumulation or gathering of a ball 16 on the end of a wire that shall contain sufficient metal from which to make cup 8 of the safety pin. This gather or ball is formed by a cumulative and progressive action 15 which consists in upsetting, in incremental steps, short lengths of wire, until a sufficient volume of metal is contained in the ball or gather from which the cup 8 may be made. The cup is formed by placing the ball in a suitable die which is shaped 20 to form the lips 9 and the channel or groove defined thereby. The gathering operation comprises feeding wire stock from a source of supply, such as a coil of wire 16', into a gathering die 17 comprising gripping jaws 18 and an upsetting member 19. The jaws and member 19 may be grooved to form a cavity of the shape which it is desired for the gather or ball 16 to take. The wire may be fed by means of pinch rolls 20 adjusted to feed the wire in uniform increments 30 into the gathering die. When the wire has been advanced an increment it is gripped between jaws 18 and the end of the wire projecting beyond the jaws is struck by member 19 and upset. This procedure is repeated until a ball or head 16 has 35 been formed at the end of the wire containing enough metal from which cup 8 may be shaped. When forming the gather of metal above described, it is preferred that the increment of feed into the gathering die shall be not greater in 40 length than approximately the diameter of the wire. In some cases, better results may be obtained with shorter increments of feed. I have also found that the amount of metal required to form cup 8 is approximately equal to not less 45 than four times the amount of metal contained in a length of four diameters of the wire. This amount of metal may be increased if necessary by increasing the number of upsetting operations. The character of the metal in the wire also has 50 to do with the amount of metal which must be gathered and the number of gathering steps employed. If the wire is of high grade spring steel, the length or increment of wire which may be upset with one blow of member 19 may be less 55 than the diameter of the wire, whereas if the metal is easily upset, longer increments may be upset with each blow of member 19.

In forming the gather illustrated in the drawing, in spring steel wire, I have employed five 60 upsetting steps and the length of wire upset in each step has been equal to one diameter of the wire. However, these specific lengths of feed and number of upsetting operations are merely examples which are given by way of explanation and 65 are not intended to be limiting in scope, as the procedure may be modified to suit the particular conditions at hand and the results to be accomplished. For example, I have found that in making pins from wire of 0.034 inch in diameter, the 70 amount of metal accumulated in the gather or ball from which cup 8 is made should be equal to the volume of metal contained in a length of four diameters of such wire. I have found also that with larger wire diameters, a sufficient amount 75 of metal may be accumulated in the ball or gather

16 with a small number of upsetting steps. In any case the amount of metal accumulated in gather 16 should be such that when it is struck in a die the maximum depth of cup 8 will be of such value that the highest points on the lips 9 of the cup 5 will project upwardly a distance greater than the diameter of bar pin 4 and above the lower end of guard 11.

When the ball or gather has been formed, the wire is cut as with shears 22, to the length required 10 to make a pin, and this length with its gather may be called a pin blank. The blank having been formed, point 5 is ground thereon. After the pin blank has been pointed as in Fig. 2, the blank is then manipulated to form the head 8. This is 15 done by forming a right angle bend in the blank as indicated at 23 and this bend forms the guard for the pin. Cup 8 is formed in a die and the bending and cupping may be done simultaneously 20 or separately in any order desired. The cupped portion of the blank is then given a right angle bend as at 24 in Fig. 4. After bending the pin blank in this fashion it is coiled around mandrel 25 to form the coil spring portion, after which the cupped end of the pin blank is bent and closed 25 on the pin point. Thus, the last operation completes the head and closes the pin.

In making pin 1', the first three steps depicted by Figs. 7, 8 and 9 are the same as the first three steps depicted by Figs. 2, 3, and 4 employed in 30 making pin 1. When the pin blank has been bent to the shape shown in Fig. 9, the head is completed by forming the close bend loop 10. When the head has been formed, the pin blank is bent around a mandrel 25 to form the coil 35 spring portion, and in completing this coil spring the bar pin is bent past the head so that when it is released, it seats in the cup 8 thereof and the pin is closed.

In making pin 2, a pin blank such as shown 40 in Figs. 2 and 7 is formed and a right angle bend is placed in the same to form the guard 11. When this bend has been formed, the gather or ball of the pin is struck in a die to form the cup 45 after which the portion between the guard and the cup is coiled into a loop 15 of substantially circular shape about a mandrel or pin. The head having been formed, the body of the pin blank is then bent around a mandrel or pin to form the coil spring portion. In making pin 2, the head 50 may be completed prior to forming the coil spring portion and closing the pin, or the coil spring portion may be made first as in Fig. 5, and then the head completed so that on completion of the head the pin is closed or locked.

Having thus described my invention, what I claim as new and desire to secure by Letters Patent is:—

1. In a method of making safety pins from a single piece of wire, the steps of upsetting a 60 length of such wire not greater than its diameter, repeating such upsetting until a head is formed containing a quantity of metal equal to at least four times the amount of metal contained in a length of one diameter of said wire, then cupping 65 the head lengthwise of the pin to form a seat for the point thereof.

2. In a method of making safety pins from a single piece of wire, the steps of upsetting, in a series of uniform steps, a head on the end of 70 the wire until it contains a volume of metal equal to at least four times the amount of metal contained in a length of at least four diameters thereof, each upsetting step involving the upsetting of a length equal to not greater than the 75

diameter of the wire, forming a cup in said head extending lengthwise of the wire, bending the wire adjacent the cupped end to form a return bend loop and a guard leg extending from 5 within and at right angles to the cup and then shaping the pin to form the back and front bars of the pin.

3. In a method of making safety pins, the steps of advancing a continuous length of wire 10 in increments equal in length to about the diameter of the wire, upsetting each increment so advanced, continuing such advancing and upsetting until a head has been formed which contains a quantity of metal at least equal to the 15 quantity contained in a length of four diameters of such wire, then in cutting a length of wire sufficient to form a safety pin, then in cupping the upset head to form a seat for the point of said pin, then in bending the cupped end of the 20 wire upon itself, bending the wire to form a guard which extends from between the lips of the cup to the back bar of the pin.

4. In a method of making the cup and guard of safety pins made from a single piece of wire 25 stock which consists in advancing wire stock in incremental steps, upsetting each increment so advanced until a head has been formed containing substantially the same amount of metal that is contained in a length of at least four 30 diameters of said stock, cutting said wire to the length required by the pin, then in cupping said head longitudinally of the wire, and then in shaping the cupped end of the wire to form a

return bend portion containing the cup and a guard portion extending from within and centrally of said cup to the back bar of the pin.

5. In a method of making the cup and guard of safety pins made from a single piece of wire 5 stock which consists in advancing wire stock in incremental steps, upsetting each increment so advanced until a head has been formed containing substantially the same amount of metal that is contained in a length of at least four diameters 10 of said stock, cutting said wire to the length required by the pin, then in cupping said head longitudinally of the wire, and then in shaping the cupped end of the wire to form a relatively short return bend portion containing the cup 15 and a guard portion extending from within and centrally of said cup to the back bar of the pin.

6. In a method of making the cup and guard of safety pins made from a single piece of wire 20 stock which consists in advancing wire stock in incremental steps, upsetting each increment so advanced until a head has been formed containing such a quantity of metal that when a cup is formed therein the depth of the cup will be sufficient to accommodate the point of the pin 25 and the lower end of the guard, cutting said wire to the length required to form the pin, then in cupping said head longitudinally of the wire, and then in shaping the cupped end of the wire to form a return bend portion containing the 30 cup and guard portion which extends from within the cup to the back bar of the pin.

FRANK MAGIDSON.
